UNITED STATES PATENT OFFICE.

ABRAHAM ZWILLINGER, OF VIENNA, AUSTRIA-HUNGARY.

APPARATUS FOR CARBONIZING BONES, &c.

SPECIFICATION forming part of Letters Patent No. 320,110, dated June 16, 1885.

Application filed October 4, 1884. (No. model.) Patented in Germany April 29, 1884, No. 29,888; in France April 29, 1884, No. 158,462; in England April 29, 1884, No. 6,995; in Belgium April 30, 1884, No. 64,998, and in Austria-Hungary September 2, 1884, No. 16,326 and No. 40,326.

To all whom it may concern:

Be it known that I, ABRAHAM ZWILLINGER, a subject of the Emperor of Austria, residing at Vienna, in Austria, have invented a certain 5 new and useful Improvement in Apparatus for Carbonizing Bones, (for which I have obtained Letters Patent in Austria-Hungary, Nos. 16,326, 40,326, dated September 2, 1884; in Germany, No. 29,888, dated April 29, 1884; in France, No. 158,468, dated April 29, 1884; in Belgium, No. 64,998, dated April 30, 1884, and in England, No. 6,995, dated April 29, 1884,) of which the following is a full, clear, and exact description.

15 This invention relates to that class of apparatus designed for carbonizing bones and other carbonaceous materials in the manufacture of gas, production of coke, or bone-block or for revivifying bone-block; and the invention consists in the construction of the apparatus and arrangement and co-operation of its various parts, substantially as hereinafter fully described.

20 My invention offers special advantages in the manufacture of bone-black or in the revivification of bone-black, either of which can be effected in a more economic manner than by any of the processes or apparatus now in use and equally as good results obtained. 25 There is a further advantage obtained in that the operation is carried out in a practically inoffensive manner, and that the by-products, especially illuminating-gas, may be collected with facility and without any danger.

30 Heretofore the carbonization of the material treated has been chiefly effected by the direct action upon such material of the products of combustion from a furnace; but it is known that the carbonization may be successfully carried out by the direct action of superheated steam or steam heated to a high temperature, inasmuch as one volume of steam at a temperature of about 932° Fahrenheit contains nearly double the quantity of heat than one equal 35 volume of the products of combustion, and by means of a specially-constructed apparatus the products of combustion from the superheating-furnace are utilized.

In the accompanying drawings, Figure 1

illustrates a vertical section of the apparatus 50 employed for carrying out my invention; Fig. 2, a section of the same on line A. B. Fig. 3 is a sectional view taken on line E F, Fig. 2, showing the construction of the superheating-furnace.

55 At one end of the apparatus is arranged a furnace divided by a wall, C, of fire-brick, into two chambers, D D, each of which is provided with a charging-door, b, and a grate, B. The rear wall of the furnace is inclined, as at a a, 60 from the grate rearwardly, so as to facilitate the combustion and also maintain the superheating-chamber at a more uniform temperature by a more rapid and uniform dissemination of the heat. The draft is regulated by the 65 adjustment of the door c of the ash-pit E.

A indicates the overheating-chamber of the apparatus, transversely of which are arranged a series of pipes, e, for conducting the steam which is to be superheated. These pipes are 70 set within walls f f, between which and the outer walls of the apparatus narrow conduits or flues f' f' are formed parallel with the chamber A, and communicating therewith by 75 passages f'. The pipes e are connected at their ends by elbow-joints d, which project into the flues f' f'. The furnace-chamber A and the flues f' f' are not arched, but simply covered by a plate or plates resting upon the walls f f.

80 The steam to be superheated is admitted to the pipes e through pipe g, connected with any suitable steam-generator, the pipes e at the front end of the apparatus being placed directly over the fire-place, so as to be more 85 thoroughly heated. Instead of arranging the steam-pipes transversely of the apparatus and parallel to each other, as shown, they may be arranged longitudinally thereof and parallel or not, as desired; or one single pipe in the 90 form of a coil may be used, arranged as nearly as possible over the fire-bed. The steam, after traversing the pipes and being superheated, is conducted by pipe h to a retort, G, or by a branch or branches of said pipe to any desired 95 number of retorts. These retorts G, which are to contain the material to be treated, may be of any suitable construction. I preferably

make them of cast-iron and of cylindrical form, the upper or charging end of which is closed by a screw-cap or cover, *i*, and the lower or discharging end by a like cap, *i'*. I preferably employ retorts having a capacity of from three hundred to four hundred pounds each of the material to be treated.

Although I have shown these retorts in an upright position, it is evident that they may be arranged in a horizontal position.

Centrally within each retort is arranged a pipe, *h*, connected with pipe *h*, said pipe *h* extending nearly the entire length of the retort, and is provided with a great number of fine 15 perforations to admit the superheated steam into the retort and project it in fine jets upon the material contained therein.

The retorts are inclosed within chambers *j,j* formed by or in the masonry of the apparatus, 20 said chambers communicating with the superheating-chamber A by a passage or flue or flues, *k*, at their lower end, and with the chimney or stack by a descending flue, *l*, the products of combustion passing from flue *l* to the 25 stack through flue *l'*, Fig. 1.

It will be seen that the products of combustion from the furnace will traverse the chamber A, completely enveloping the pipes *e,d*, and will then pass through passage *k* into the 30 retort-chambers *j,j* to maintain the same at such a temperature as to prevent loss of heat by radiation and consequent condensation of the steam within the retorts.

The gases and vapors generated by the carbonizing process pass through pipes *m* from the upper portion of the retorts and through connections *m'* to a condenser, H. From the latter the gases are conducted by pipes *n* to a refrigerator.

40 By means of a siphon, *o*, which leads from the condenser to the washing-basins, the ammoniacal water is kept at a uniform level in said condenser.

To prevent the steam-pipes and retorts from 45 becoming oxidized, I coat the same with any suitable neutral body or compound—preferably with a composition of my invention, which answers the purpose admirably and which is capable of resisting high temperatures without cracking. It is composed of one hundred parts of refractory clay, twenty parts ordinary clay, forty parts of carbonized bone, and two parts cow-hair, prepared as follows: The refractory clay, ordinary clay, 50 and the carbonized bone are finely ground, and then reduced to a plastic mass by the addition of water with which the cow-hair is thoroughly mixed.

In revivifying bone-black the same may be 55 filled into the retorts in a wet state.

To avoid reflux of the steam in the steam and superheated-steam conduits due to pressure in the retorts the pressure in the steam-

generator should always exceed by one or two atmospheres the pressure in said retorts. 65

The masonry of the apparatus should be of such thickness as to avoid as much as possible the loss of heat by radiation.

The described apparatus may be used to advantage for the manufacture of lighting gas 70 extracted from pit-coal, and the by-products collected.

Having now described my invention, what I claim as new, and desire to secure by Letters Patent, is—

1. In an apparatus of the class described, the combination, substantially as set forth, of one or more closed retorts for the material to be treated, a perforated pipe arranged therein and extending nearly the full length of 80 such retort, a steam generator, a superheater, and connecting-pipes for connecting the retort-pipe with the superheater and the latter with the generator, for the purpose specified.

2. In an apparatus of the class described, 85 the combination, substantially as set forth, of one or more retorts, a liquid seal for sealing said retorts, a perforated pipe arranged in and extending nearly the entire length of said retorts, a steam-generator, a steam superheater, 90 and connecting-pipes for connecting the superheater with the generator and the retort-pipe, for the purpose set forth.

3. In an apparatus of the class described, the combination, substantially as set forth, of 95 one or more sealed retorts, a perforated pipe arranged in and extending nearly the entire length thereof, and a steam-generator, with a superheating-furnace, and a series of connected pipes arranged in the combustion-chamber 100 of the furnace, said pipe having its initial or point of connection with the steam-generator farthest from the source of heat of said furnace and its terminal or point of connection with the retort-pipe nearest to or at the source 105 of heat, for the purpose set forth.

4. In an apparatus of the class described, the combination, substantially as set forth, with a steam-generator and a superheating-furnace, 110 of a series of connected pipes in communication with the generator, one or more sealed retorts, a perforated pipe arranged in and extending nearly the entire length of said retort or retorts, and connections for connecting the retort-pipe with the superheating-pipe, 115 said superheating-pipes and retorts being located in the combustion-chamber of the furnace or a continuation thereof, for the purpose set forth.

In testimony whereof I affix my signature in 120 presence of two witnesses.

ABRAHAM ZWILLINGER.
